UNITED STATES PATENT OFFICE.

WILLIAM KILLION, OF BOSTON, MASSACHUSETTS.

DESIGN FOR A HORSESHOE-PAD.

SPECIFICATION forming part of Design No. 32,706, dated May 22, 1900.

Application filed April 23, 1900. Serial No. 14,058. Term of patent 14 years.

To all whom it may concern:

Be it known that I, WILLIAM KILLION, a citizen of the United States, residing in Boston, in the county of Suffolk and State of Massachusetts, have invented a new and original Design for Horseshoe-Pads, of which the following is a specification, reference being had to the accompanying drawings, forming part thereof.

10 Figure 1 is a perspective view of my horseshoe-pad, taken from the upper side. Fig. 2 is a central transverse vertical section. Fig. 3 is a perspective view taken from the under side.

15 As shown in the drawings, the leading or material feature of my design consists of the configuration of the pad formed with the base, having forwardly-projecting steps, *a* being the front edge, concave or formed on a curve 20 or arc, as shown; *b*, the rear edge, on a straight line; *c c*, forwardly-projecting steps the surfaces of which are inclined upward toward the rear, the inner edges *d* rounded or curved

at the corners, and the outer edges *e* slightly curved, as illustrated. The lift or pad proper, 25 *f*, extends up from the base and has a flat surface, its front edge *h* being beveled back from the front edge *a* and conforming to the curvature of said front edge. The curvature is on such an arc as to produce the forward 30 extensions *f'* at the inner edges of the steps *c*, the outer sides of the said extensions being vertical. The rear edge *g* of the pad is on a straight line and is set slightly forward from the edge *b*, so as to produce a ledge *n*. The 35 edges or sides of the pad follow the curvatures of the base.

Having described my invention, what I claim as new, and desire to secure by Letters Patent, is—

40 The design for a horseshoe-pad, as herein shown and described.

WILLIAM KILLION.
